228,083

COMBINED MEMO PAD HOLDER, WRITING INSTRUMENT AND HOLDER THEREFOR

Roland Longarzo, Valley Stream, N.Y., assignor to Consolidated Foods Corporation, Chicago, Ill.

Filed Dec. 2, 1971, Ser. No. 204,398

Term of patent 14 years

Int. Cl. D19—02
U.S. Cl. D45—9 A

FIG. 1 is an exploded perspective view of a combined memo pad holder, writing instrument and holder therefor showing my new design;

FIG. 2 is a right side elevational view thereof;

FIG. 3 is an upper end view;

FIG. 4 is a lower end view;

FIG. 5 is a bottom plan view thereof;

FIG. 6 is a perspective view of another embodiment of the combined memo pad holder, writing instrument and holder therefor shown in FIG. 1;

FIG. 7 is a left side view thereof; and

FIG. 8 is a bottom plan view thereof.

I claim:

The ornamental design for a combined memo pad holder, writing instrument and holder therefor, substantially as shown and described.
